DESIGN FOR AN ELECTRIC BELL

Jacob L. Rifkin, Long Island City, N. Y.

Application March 22, 1947, Serial No. 137,809

Term of patent 14 years

(Cl. D26—13)

To all whom it may concern:

Be it known that I, Jacob L. Rifkin, a citizen of the United States, residing at Long Island City, in the county of Queens and State of New York, have invented a new, original, and ornamental Design for an Electric Bell, of which the following is a specification, reference being had to the accompanying drawing, forming a part thereof.

In the drawing:

Fig. 1 is a top plan view of an electric bell, showing my new design;

Fig. 2 is a front elevational view; and

Fig. 3 is a rear elevational view of the same.

I claim:

The ornamental design for an electric bell, as shown.

JACOB L. RIFKIN.
